UNITED STATES PATENT OFFICE.

JOHN M. JOY, OF NEW YORK, N. Y., ASSIGNOR TO PAGE MACHINE COMPANY, OF NEW YORK, N. Y., A CORPORATION OF NEW YORK.

MEANS FOR TRANSMITTING POWER.

No. 860,873.

Specification of Letters Patent.

Patented July 28, 1907.

Application filed January 20, 1905. Serial No. 242,024.

To all whom it may concern:

Be it known that I, JOHN M. JOY, a citizen of the United States, residing at New York, in the county of New York, State of New York, have invented certain new and useful Improvements in Means for Transmitting Power, of which the following is a specification.

My invention relates to means for transmitting power, and has for its object to provide improved and simple means whereby power from a proper source may be transmitted to, and properly stored with relation to, an operating device, whereby the power may be utilized as desired and whereby the storage of the power to be utilized may be automatically regulated and controlled, and to these ends my invention consists in the various features of construction arranged and operating substantially in the manner hereinafter more particularly set forth.

Referring to the accompanying drawings, wherein is illustrated one embodiment of my invention, Figure 1 is a vertical elevation of an apparatus embodying my invention; Fig. 2 is a side view thereof; Fig. 3 is a partial plan view; and Fig. 4 is a detail.

It is often desirable to provide an operating device wherein the power to operate it is stored under tension so that it will be under constant stress and so that when released it will furnish power to accomplish the results desired, and when the power thus stored is utilized to a greater or less extent it is desirable to automatically store more power ready for another operation.

The present device was particularly designed for use in printing telegraph instruments, but is obviously applicable to other uses.

The object of my present invention is to provide a simple and effective means whereby this general result may be accomplished and whereby power from a given source can be transmitted to an operating device and stored, so to speak, under tension, causing said operating device to be under a constant stress ready for operation when released for that purpose.

In the embodiment illustrated herein, A represent the operating device or driven element which in this instance is shown in the form of a shaft which is under stress and which may be connected to operate any suitable or desirable device. The operation of this shaft may be controlled in any suitable way, and in the present instance I have shown a ratchet or escapement wheel W, which may be controlled in any convenient way, as by the ratchet or escapement W', whereby the power stored in the driven element or operating device can be intermittently utilized as desired. Connected to this driven element is a tension device adapted to receive and store power, and it is shown in the present instance in the form of a spiral spring B, one end of which is secured to the driven element or shaft A in any

suitable way, as by the collar b connected to one end of the spring and secured to the shaft as by a screw b', and the other end of the spring is connected to a worm wheel D which is loose on the shaft A. The source of power or driving element in this instance is represented by the part E, which in the present instance comprises a sleeve mounted on the support or shaft F and receiving power through any suitable source, as, for instance, the shaft S which is connected to be driven by a suitable motor S' and to transmit the power from the motor to the source or driving element by means of gears S², S³. In the present instance to transmit the power from this driving element to the tension device of the driven element, I provide a clutch mechanism, one member C of which is connected to the driving element and may be said to be relatively fixed, while the other member C' is relatively movable and is operatively connected to the driven element. This movable member C' of the clutch is shown in the form of a sleeve loose on the shaft F, and in the present instance it is provided with a worm wheel G adapted to engage the co-operating worm wheel D connected to the tension device and thereby with the driven element.

Some means should be provided tending to cause the engagement of the clutch members, and when the parts are arranged in the positions shown in Fig. 1, the weight of the movable member C' and its connected worm wheel tends to cause engagement of the clutch members, and under some conditions this is sufficient for the purposes, but preferably I provide additional means shown in the form of a weighted or spring-actuated arm H, having in the present instance a friction roller h bearing on some portion of the movable member, tending to cause engagement of the clutch members and actuated in the present instance by a spring h' mounted on a stud or bearing h², one end of the spring being secured to the collar h³ and the other end bearing on the arm H, as best seen in Fig. 3. The tension of this spring can be adjusted by turning the collar h³ on its bearing h² and securing it by the adjusting screw h⁴. It is also desirable to provide means for preventing the backward rotation or movement of the movable clutch member when it is disengaged from the fixed clutch member, through the reaction of the tension device, and when the worm wheels connecting the tension device and the movable clutch member are provided with teeth cut at a comparatively steep angle, as represented in the drawing, advantage can be taken of this construction to prevent the backward rotation or movement of the movable clutch member through the friction of the parts. When, however, this is not sufficient, and preferably in actual practice, I provide additional means for accomplishing this result. In the present instance this means is represented in the pawl I which is shown as conveniently attached to the arm H, as be-

ing under tension of the spring i and as engaging the ratchet wheel I' on the movable clutch member. These devices as thus far described may be suitably mounted in any suitable support or frame and in the 5 present instance I have shown a base 1 , to which is attached an upright 2 having a bracket 3 , and the various parts are mounted and supported therein as indicated.

So far I have described a single driven element and its connection with the driving element, but in actual 10 practice in many instances it is desirable to have more than one driven element or operating device, and I have shown at A' a second driven element or shaft to which is connected a second tension device or spring B' and worm wheel D' , and mounted on the shaft F is a second 15 movable clutch member C' which is provided with a worm wheel G' engaging the worm wheel D' . This second movable member in the position shown has to be provided with some extraneous means tending to cause engagement of the movable member with the 20 fixed member, and I have shown the rocking arm J mounted on a stud J' in the bracket 4 and having a friction wheel j bearing against the movable member. This arm is under stress of the spring j' adjustably secured to the stud J' by the collar j^2 and screw j^3 . The 25 tension device or spring B' in this instance is shown enclosed in a sleeve B^2 which is practically an extension of the collar b , and this serves to protect the tension device from injury.

Having thus described the particular embodiment 30 of the present invention illustrated in the drawings, its mode of operation will be largely understood from what has been set forth, but it can be further stated as follows. Assuming that the driving element or relatively fixed member of the clutch is constantly driven from the source of power, the movable clutch member C' tends to remain in engagement therewith either through 35 its weight or through the pressure of the arm H thereon, so that the movable member rotates in unison with the fixed member of the clutch. This rotates the worm 40 wheel G , and this by engagement with the worm wheel D tends to wind up the spring or tension device B , so that the tension device exerts a stress upon the driven element or operating device A , tending to rotate the same. As soon as the stress on the tension device is 45 sufficient to overcome the weight or tendency of the movable clutch member to engage with the fixed clutch member, the movable clutch member is automatically raised or moved on the shaft F so as to disengage the clutch members, and the power stored in the tension device is retained either through the friction between 50 the worm wheels or by the additional retaining device in the form of the pawl I and ratchet wheel I' . Thus a certain definite power is stored in the tension device and the driven element is under certain definite stress, 55 tending to operate the same, and when by suitable means, as the escapement wheel W and escapement W' , the driven element is released, the tension device reacts to operate the driven element and do the work desired. As soon as the stress on the tension device is reduced 60 sufficiently, the movable member of the clutch moves, either under its own weight or the pressure of the arm H , so that the clutch members are brought into engagement, and thus the tension device is again operated and put under further stress so as to practically maintain a 65 substantially constant stress upon the driven element.

This operation is automatic, the clutch being engaged and disengaged so as to operate the tension device in accordance with the amount of power stored therein.

It will thus be seen that the driven element may be put under any desired stress and be ready to operate 70 and exert said stress or force for any useful purpose when released, and that as soon as this stress is reduced the transmitting mechanism is automatically operated to restore the tension to the tension device, and as soon as it receives the desired amount of tension the 75 transmitting device is automatically put out of operation and the clutch members disengaged, so that the tension device will not be injured and the tendency to backward movement of the tension device and movable clutch member is prevented so that the stress is constantly maintained on the tension device.

What I claim is:—

1. The combination with a driving element and a driven element, of clutch members interposed between the two elements, and a tension device operating the driven element and operated by one of the members of the clutch, said tension device operating automatically to disengage the clutch members under a given degree of tension, substantially as described. 85

2. The combination with a driving element and a driven element, of clutch members interposed between the two elements, one of the clutch members being relatively fixed and the other relatively movable, and a tension device operating the driven element and operated by the movable member of the clutch, said tension device operating automatically to permit engagement of the clutch members under a given tension and to disengage the said members under a higher tension, substantially as described. 95

3. The combination with a driving element and a driven element, of clutch members interposed between the two elements, means tending to cause engagement of the clutch members, and a tension device between the driven element and clutch members and operating to disengage the clutch members by overcoming the tendency of said engaging means, substantially as described. 100

4. The combination with a driving element and a driven element, of clutch members interposed between the two elements, means tending to cause engagement of the clutch members, a tension device between the driven element and clutch members and operating to disengage the clutch members by overcoming the tendency of said engaging means, and means for preventing the backward movement of the movable clutch member and tension device, substantially as described. 110

5. The combination with a driving element and a driven element, of clutch members interposed between the elements, one of which members is connected to the driving element, and is relatively fixed, the other of which members is connected to the driven element and is relatively movable, means tending to cause engagement of the clutch members, a tension device connecting the driven element and the movable member of the clutch and operating to disengage the clutch members, and means for preventing the backward movement of the movable clutch member and tension device, substantially as described. 115

6. The combination with a driving element of a driven element, means for transmitting power from the driving element to the driven element including an automatically operating clutch and a spring tension device, means for normally preventing the release of the tension device and means for controlling the motion of the driven element under the influence of the tension device, substantially as described. 130

7. The combination with a driving shaft having mounted thereon a fixed clutch member and a movable clutch member, of a driven shaft, a sleeve on said driven shaft having gear connections with the movable clutch member and a tension device connected to the driven shaft and to the sleeve thereon, substantially as described. 135

8. The combination with a driving shaft having mounted thereon a fixed clutch member and a movable clutch mem-

ber, of a driven shaft, a sleeve on said driven shaft having gear connections with the movable clutch member and a tension device consisting of a coiled spring connected at one end to the driven shaft and at its other end to the sleeve thereon, substantially as described.

9. The combination with a driving shaft having mounted thereon a fixed clutch member and a movable clutch member, of a driven shaft, a sleeve on said driven shaft having gear connections with the movable clutch member and a tension device connected to the driven shaft and to

the sleeve thereon, means for preventing reverse motion of said sleeve, and means for controlling the rotation of the driven member under the influence of the tension device.

In testimony whereof I have signed my name to this 15 specification in the presence of two subscribing witnesses:

JOHN M. JOY.
